UNITED STATES PATENT OFFICE.

MYER METZGER, OF CHICAGO, ILLINOIS.

DESIGN FOR A COMBINED VENDING AND DISPLAY STAND.

55,809.

Specification for Design.

Patented July 13, 1920.

Application filed February 5, 1920. Serial No. 356,402. Term of patent 7 years.

To all whom it may concern:

Be it known that I, MYER METZGER, a citizen of the United States, residing at Chicago, in the county of Cook and State of Illinois, have invented a new, original, and ornamental Design for a Combined Vending and Display Stand, of which the following is a specification, reference being had to the accompanying drawing, forming part thereof.

Fig. 2 is a top plan view.

I claim:

The ornamental design for a combined vending and display stand, as shown.

MYER METZGER.
